DEVICE FOR CLEANING THE GRILLE OF HYDRAULIC INSTALLATIONS

Jean Sturzenegger, Geneva, Switzerland, assignor to Atelier de Construction Jonneret S. A., Geneva, Switzerland, a corporation of Switzerland

Application November 4, 1953, Serial No. 390,144

Claims priority, application Switzerland November 11, 1952

3 Claims. (Cl. 210—176)

This invention relates to a device for cleaning the grille of hydraulic installations, such as hydroelectric power plants, pumping installations, such, for example, as set forth in my co-pending application Serial Number 390,143 filed November 4, 1953.

The present device is of the type comprising a carriage adapted to be displaced along the grille, a cradle being rockably secured to the frame of the said carriage, the said cradle serving as a receptacle for the detritus or debris lodged against the grille, at least one cable being provided for the control of the carriage and the cradle.

In previous arrangements of this kind, the cleaning or clearing of the grille proceeds only during the ascending movement of the carriage against the grille, the cradle, which in most cases is provided with teeth or prongs, collecting the detritus or debris along the grille. Thus, only the ascending movement is effective for the cleaning.

Moreover, the arrangements operating according to the aforementioned principle have the disadvantage of dispersing the debris on the portion of the grille to be cleaned while the carriage descends into the water. As a result, when the carriage is raised, the cradle picks up only a fraction of the debris lodged against that part of the grille which is to be cleaned, and the floating materials that had accumulated against the upper part of the grille are scattered over the surface of the water so that they cannot be removed in an efficient manner.

Furthermore, in the known arrangements, during the descent of the carriage, the rollers of the carriage roll over the debris lodged against the grille. This results in poor guiding of the carriage and possible blocking of the rollers.

The device according to the present invention tends to remedy the aforementioned disadvantages. It is characterized by the fact that the carriage is provided opposite the cradle with a grille portion, as shown in the drawings, the latter including bars whose ends extend downward from the carriage to collect during the downward movement of the carriage the debris retained by the grilles of the hydraulic installations in such a way that the rollers of the carriage move along a path unobstructed by foreign bodies, and cooperating means on the carriage and cradle to positively close the cradle in relation to said extended ends of the bars of the grille portion. The accompanying drawing shows, diagrammatically and by way of example, an embodiment of the cleaning or scavenging device forming the subject matter of the invention.

Figure 1 is a horizontal elevational view, with portions broken away, of the scavenging device disposed against the grille of a hydraulic installation.

Figure 2 is a section along II—II of Fig. 1.

Figure 3 is a side view of the carriage in the descending position with the cradle open.

Figure 4 is a view, similar to the previous one, of the carriage in the ascending position with the cradle closed.

2

Figure 5 is a detail partial perspective view of a portion of the cradle.

Figure 6 is a side view of another embodiment.

As shown in Figs. 1 and 2, the device for cleaning the grille of a hydraulic installation comprises a carriage 1 adapted to be displaced along the grille of a hydraulic installation, such as a hydroelectric power plant or a pumping installation.

This carriage 1 comprises a frame 3 of generally U shape and which is mounted on two pairs of rollers 4 adapted to roll on the bars 5 of grille 2. Each roller is provided with a rib 6 to guide the rollers along the grille bars 5.

The carriage 1 supports a rockably mounted scavenging device in the order of a clam shell bucket or cradle 7 and which primarily consists of a piece of sheet metal substantially co-extensive with the width of the carriage to provide a receptacle for collecting the debris in front of the grille. The cradle 7 constituted as just described

is also provided at the opposite ends thereof with a pair of frame members 8 which have their forward portions of arcuate formation to support and hold the sheet metal portion 7a while the ends of the frame members extending beyond the inner edge of the sheet metal portion 7a provide levers 8a. The frame members including the levers 8a are pivoted to the carriage as indicated at 9, and, as will appear from the drawings, the free edge of the sheet metal scoop portion of the cradle may be provided with claws 10 to facilitate handling of the debris.

In order to effectuate the operation of the carriage and the portions of the cradle, preferably several groups of cables are provided. One group operates parts of the cradle and the other group includes the main cables for lifting and lowering the carriage.

In the form of construction shown in the drawings, the group of cables for operating the cradle are identified as 11 and 13a—13a. The cable 11 is secured at its lower end to the medial portion of the scoop of the cradle, as indicated at 12, as will be apparent from Figures 1 and 3.

The remaining cables 13a are connected at their lower ends to the levers 8a of the cradle disposed at the side of the pivot 9 opposite the edge of the cradle including the claw 10.

The upper end of the single cable 11 is connected to a winch (not shown), while the upper ends of the cables 13a are connected to the outer ends of the equalizing bar 15, as will be apparent from Figure 1. It will also be seen from the drawings that the equalizing bar 15 is guided in two slotted supporting members 16 connected with the upper portion of the carriage. Thus, the equalizing bar 15 is guided substantially parallel to the direction of displacement of the carriage in relation to the grille.

The second group of cables 13 have their lower ends connected to the medial portions of the equalizing bar and their upper ends are connected to a winch, not shown. These cables control the sliding movement of the carriage 1 relative to the grille 2.

A row of teeth or prongs 18 intended to pick up the debris lodged against the grille, while the carriage descends along the grille, are hinged to the crosspiece 17 by means of a shaft 19. Prongs 18 are integral with one another through a plate 20. At each end of the row of prongs is an actuating camming arm 21 whose nose 22 provides a camming edge to raise prongs 18 when the carriage passes over a cross-bar 23 of the grille 2.

Means for controlling the raising of said prongs 18 when cradle 7 is closed consist of a second arm 24 extending rearwardly beyond the point where the prongs are linked to the carriage. Edge 25 of said second arm cooperates during the closing of the cradle with a roller

26 mounted near the free end of the corresponding lever
8a of the cradle.

As shown in Figs. 1 and 2, the carriage is constructed in such a way as to form a receptacle, the bottom of which opens downwardly and is provided with grilles on both sides of frame 3. The inner grille is formed by bars 27 disposed parallel to one another and spaced apart by a distance substantially equal to the spacing of bars 5 of grille 2. The outer grille is formed by bars 28 spaced closer together than the bars of the inner grille. The frame 3, in effect, forms the top of the receptacle. As will be seen in the Figures 3 and 4, the upper grille formed by the series of parallel bars 28 is movable. To that end, the bars 28 have their upper ends slidably connected by means 29 to the carriage while their lower ends are pivotally secured to the shaft 30 carried by the cradle 7. In that connection, the movable grille bars 28 of the carriage each may have their lower ends connected to the shaft 30, or, alternatively, the grille bars 28 arranged as a unit may have a connection with the arcuate frame members 8 at the ends of the sheet metal portion of the cradle to be controlled thereby.

Thus, as shown by Figure 3, in the open position of cradle 7, bars 28 are farther from the fixed bars 27 than in the closed position of the cradle, as per Figure 4. The angular displacement of bars 28 would facilitate the unloading of the receptacle from the cradle when the carriage 7 is opened.

Moreover, a push rod may be provided at the top of the receptacle to dispel the debris from the receptacle when the cradle is opened. Such push rod could be controlled by the equalizing bar 15.

As another modification shown in Figure 6, as above set forth, the prongs 18 are stationary instead of being rockably secured to the carriage as in my companion application Serial Number 390,143, filed November 4, 1953, and as described hereabove with reference to Figures 1 to 5. In this case the prongs 18 would be formed by an extension of the grille bars 27 at the inner face of the carriage, and could be applied, either alone or in combination with the open work receptacle, to any carriage of known construction provided with any type of cradle controlled either by an independent cable, or automatically by a cable secured to the carriage.

The operation of the device herein described is as follows:

When not in use, carriage 1 is held at the top of grille 2 by cables 11 and 13, controlled by one or several winches (not shown) set up in the control cabin of the hydraulic installation.

When the device is to be used, cables 11 and 13 are unwound at substantially the same rate of speed to enable the carriage to descend along the grille 2, its cradle then being in the open position as shown in Figure 3.

During this descending movement, the materials floating on the surface of the water in which grille 2 is immersed enter the receptacle formed by the carriage proper. The prongs 18 act to disengage from the latter any debris lodged against it, the grille bars 27 and 28 allowing the water to pass therethrough, but retaining the debris.

When prongs 18 pass over a cross-bar 23, the cam-forming edge 22 of arms 21 assures the retraction of said prongs from the grille.

As soon as the carriage reaches the lower part of the grille, the winch controlling cable 13 is stopped, while the winch controlling cable 11 continues to unwind that cable. Thus, cradle 7 is closed by a rocking movement due partly to the action of its own weight because cable 11 is slack and partly to the action of the weight of the carriage 1 which presses on the levers 8a of said cradle pivotally secured to the carriage at 9. Thus thrust of the carriage assures a perfect closing movement of

the cradle. During this rocking movement, cradle 7 pivots about point 14 of levers 8a.

Simultaneously with the closing movement of the cradle, prongs 18 retract from grille 2. In fact, while the cradle rocks, rollers 26 enter into contact with arcuate edge 25 of actuating arms 24 and push the same backward. The motion imparted to prongs 18 through arms 24 together with the action of the cradle and of the upper grille formed by the bars 28 results in a firm gripping of the materials engaged in the cradle and in the receptacle formed by the carriage. Once the cradle is closed, the winch controlling cables 13 winds these cables, and the carriage is brought back to the upper part of the grille.

15 The fastening of cables 13a at the free end of levers 8a of the cradle prevents premature opening of the cradle. After having been brought near the control cabin, carriage 1 and its cradle 7 can be unloaded of the debris which they contain, either into a canal or into a truck 20 provided for their disposal.

A cleaning or scavenging device such as herein described and illustrated makes it possible to clean grilles rapidly and efficiently because as soon as the carriage begins its descending movement, the materials floating on the surface of the water enter the lower end of the open work receptacle formed by the carriage proper.

During the entire descent of the carriage, the teeth or prongs 18 disengage the debris caught by the bars of the grille 2. Thus, the debris is gathered in the receptacle formed by the carriage. After the carriage reaches the bottom of the grille, debris of large volume, such as branches and tree trunks, are held fast by the teeth or prongs 18 and the cradle 7 and the carriage loaded with debris is retracted toward the top of the grille 2 for unloading. Thus, any dispersion of floating materials or any scattering of debris is prevented, and that portion of the grille over which the carriage is displaced is readily cleaned by a single operation.

Moreover, the carriage is properly guided in its descending movement by the bars 5 of the main grille or strainer 2; thus the grille is freed from debris during the initial phase of the cleaning operation. Therefore, there is no possibility of the rollers 4 being blocked by debris.

I claim:

45 1. A device for cleaning the grillwork of hydraulic in-
stallations, said grillwork having a cross bar, comprising,
in combination, a carriage member adapted to be moved
along said grillwork, said carriage member including an
inverted U-shaped frame, two pairs of roller members
50 mounted respectively at the open and closed ends of the
U-shaped frame for supporting said frame upon the grill-
work in rolling reciprocating relationship parallel to the
legs of the U-shaped frame, a stationary inner grillwork,
55 an angularly displaceable and movably mounted outer
grillwork, said grillworks extending respectively over op-
posite open faces of the U-shaped frame, means for mova-
bly mounting said outer grillwork to said carriage at one
end in an angularly displaceable manner, a cradle mem-
ber rockably secured to said carriage member on an axis
60 passing through both free ends of the legs of the U-shaped
frame and rockable over and away from the open end of
the U-shaped frame, said means for movably mounting
said outer grillwork including a shaft member connected
65 to said cradle member and a means for slidably connect-
ing said grillwork to the carriage at the end of said car-
riage opposite to the end at which said cradle is rockably
secured thereto, lever members fixed to said cradle hav-
ing free ends extending to the opposite side of said pivot
70 axis from said cradle, each lever member having a roller
member attached at the respective free end thereof, means
for controlling the carriage and the cradle in their si-
multaneous movement along said grillwork, one portion
75 of said means being operatively connected to said cradle
and the other portion of said means being operatively

connected to each of said lever members at the free ends thereof, prong means operatively connected to said carriage at one end thereof for dislodging debris from said grillwork upon movement of said cradle and said carriage in one direction along said grillwork, claw means attached to said cradle for facilitating the handling of the said so dislodged debris upon movement of said cradle and said carriage in the opposite direction along said grillwork, means for raising said prong means upon the contacting thereof with said grillwork cross bar, said raising means being operatively connected to said prong means and having at least one arm operatively connected to said carriage member at the frame member sidewall, said arm having a cam shaped edge at one end thereof and a curved edge at the other end thereof.

2. The apparatus of claim 1 wherein the means for

raising said prong means includes a crosspiece member attached to the carriage and a shaft operatively connected to said crosspiece, said arm being movably mounted on said shaft, said prong means being operatively connected to said arm.

3. The apparatus of claim 1 wherein the means for controlling the carriage and the cradle in their simultaneous movement along said grill work includes a cable operatively connected to said cradle and cables respectively connected to said lever member.
